ARMORED CABLE CUTTER

Clark D. Belden, Minneapolis, Minn.

Application November 1, 1948, Serial No. 57,680

11 Claims. (Cl. 30—91)

1

My invention relates generally to cutting tools and, more specifically, to a tool for cutting the armor or casing of armored cable such as BX or "Greenfield" cable.

An important object of my invention is the provision, in a tool as set forth, of cable-gripping jaw inserts which are quickly and easily removable from the tool so as to permit replacement thereof by other jaw inserts adapted to securely grip cables of different diameters.

Another object of my invention is the provision of an armored cable-cutting tool in which a cutting blade is disposed so as to sever at least one convolution of helically-wound armor without danger of cutting into the electric conduit carried therein.

Still another object of my invention is the provision of means for retaining the manually-operated cutting blade handle of my device closely adjacent and parallel to the other handles thereof, whereby to form a compact structure for storage and shipping.

A still further object of my invention is the provision of a cutting tool as set forth which is inexpensive to build, simple to operate, rugged in construction, and durable in use.

Other highly important objects and advantages will become apparent from the following detailed specification, appended claims, and attached drawings.

Referring to the drawings, in which like characters indicate like parts throughout the several views:

Fig. 1 is a view in perspective of my improved cutting tool in an open position, some parts being removed and some parts broken away;

Fig. 2 is a fragmentary view corresponding to Fig. 1 but having removable gripping jaw inserts applied thereto;

Fig. 3 is an enlarged detail in section taken on the line 3—3 of Fig. 2;

Fig. 4 is a plan illustrating the use of my cable-cutting tool, some parts being broken away; and

Fig. 5 is a view partly in section and partly in end elevation, taken substantially on the line 5—5 of Fig. 4.

My improved armored cable-cutting tool resembles a pair of pliers, and comprises a pair of gripping elements or jaws 1 and 2 which are pivotally secured to each other by a pintle or pivot pin 3. Extending outwardly from the gripping jaws 1 and 2 are handle portions 4 and 5 respectively. Said handle portions 4 and 5 project at an oblique angle to the axis of the pivot pin 3 and lie in closely-spaced parallel re-

lationship when the gripping jaws 1 and 2 are in a position to embrace a portion of armored cable. Each of the gripping jaws 1 and 2 is provided with a recess 6 that extends parallel to the axis of the pivot pin 3, and which is adapted to receive a gripping jaw insert 7. The jaw inserts 7 fit snugly in the recesses 6 and are provided at both ends with outwardly-projecting lugs 8 which fit corresponding channels 9 in the gripping jaws 1 and 2 to prevent movement of the inserts in a direction parallel to the axis of the pivot pin 3. The inner or opposing surfaces of the lugs 8 are provided with recesses or cavities 10 that receive spring-pressed ball detents 11 when the jaw inserts 7 are seated in the recesses 6. As shown in Figs. 1 and 3, the detents 11 project outwardly from the gripping jaws 1 and 2 into the channels 9. Engagement of the detents 11 with the cavities 10 of the jaw inserts 7 prevents accidental removal of the jaw inserts from the gripping jaws 1 and 2. The jaw inserts 7 are each formed to provide channels 12, which, when the inserts 7 are contained in the gripping jaws 1 and 2, extend parallel to the axis of the pivot pin 3. The channels 12 are formed with teeth or ribs 13 which form sections of a helix. The ribs 13 and spacing therebetween are of a size to fit the convolutions of spirally-wound armored cables such as BX. When the gripping jaws 1 and 2 are closed as indicated in Figs. 4 and 5, the channels 12 frictionally grip diametrically-opposite sides of the armored cable indicated by the letter A, which anchors the same against axial and rotating movements therebetween, see particularly Figs. 4 and 5. The armored cable A shown in the drawings may be presumed to be the type known as BX. When it is desired to apply my cutting tool to cable of larger diameters such as "Greenfield" cable, it is but necessary to remove the jaw inserts 7 from the recesses 6 and apply other jaw inserts, not shown. Such other inserts may be assumed to be similar to the inserts 7 except that the channels 12 will be wider and deeper to accommodate such larger diameter cable.

A cutting blade 14 is pivotally-secured adjacent its inner end to the gripping jaw 1 by means of a nut-equipped shoulder bolt or the like 15. The opposite gripping jaw 2 is provided with a recess 16 to receive the head of the bolt 15 when the gripping jaws 1 and 2 are closed, see particularly Figs. 1, 2, and 5. The cutting blade 14 is provided at its inner end with an arcuate cutting edge 17 which, upon pivotal movements of the blade 14, is adapted to move into and out

of cutting engagement with the armored cable A held between the gripping jaws. The blade 14 extends laterally outwardly from the pivot bolt 15 and terminates in a handle lever 18 adapted to be gripped by one of the operator's hands at the same time as the handle portions 4 and 5 are held in the operator's other hand. While thus held, the blade 14 may be moved from its dotted line position of Fig. 4 to the full line position thereof, thereby causing the arcuate cutting edge 17 of the blade 14 to sever at least one convolution of the armor of the cable A. It will be seen by reference to Fig. 5 that the cutting edge 17 penetrates the armor of the cable A but does not extend to any appreciable distance inwardly thereof. Injury to the insulation or wires which may be contained therein is thus prevented. When the tool is used to cut cable of larger diameter, such as "Greenfield" cable, the cutting blade will penetrate a greater distance into the interior of the cable. However, in most instances, the larger diameter "Greenfield" cable is wired subsequent to its being cut, so that no damage occurs to the wires therein. It will be noted that the axis of the pivot bolt 15 is perpendicular to the axis of the pivot pin 3, so that movement of the cutting edge 17 of blade 14 is in a plane parallel to the axis of the cable A.

I provide stop means limiting movements of the cutting blade 14 and handle lever 18 thereof in one direction in the nature of a pin or boss 19 extending transversely outwardly of the handle portion 5. During cutting movements of the blade 14 with respect to the handles 4 and 5, one side edge of the blade 14 will abut the boss 19 to limit movement of the blade 14 toward the handles 4 and 5. The blade 14 is provided with an aperture 20 which is equidistant from the pivot bolt 15 and the boss 19. When the tool is in its open position as in Figs. 1 and 2, the blade 14 may be moved about the axis of the pivot bolt 15 to a position adjacent and parallel to the handle 4. When the tool is then closed, the boss 19 will be received within the aperture 20 and the blade 14 will be prevented against pivotal movements in either direction and the tool will be disposed in a compact form for storage or shipment. During a cable armor-cutting operation, engagement of the adjacent side edge of the blade 14 with the boss 19 prevents the operator's hands from striking one another and being bruised or otherwise injured. When a cut has been made from one edge of the convolution to the other thereof, the cutting tool is then removed from the cable and as much of the cable may then be unwound as desired.

My invention has been thoroughly tested and found to be entirely adequate for the accomplishment of the objectives set forth, and while I have shown and described a preferred embodiment thereof, it will be understood that the same is capable of modification without departure from the scope and spirit of the invention as defined in the claims.

What I claim is:

1. A tool for cutting armored cable comprising a pair of pivotally-connected armored cable-gripping jaws, handle portions extending outwardly of said gripping jaws and adapted to lie in closely spaced parallel relationship one with the other when said gripping jaws are closed about said armored cable, a cutting blade pivoted to one of said handles on an axis perpendicular to the pivot axis of said gripping jaws, and a handle lever on said cutting blade, said handle lever ex-

tending radially outwardly of the pivot axis of said blade, the cutting edge of said blade being adapted to move into and out of cutting engagement with said armored cable upon pivotal movements of said handle lever and blade in opposite directions.

2. The structure defined in claim 1 in further combination with stop means limiting pivotal movements of said cutting blade in one direction.

10 3. A tool for cutting armored cable comprising a pair of pivotally-connected armored cable-gripping jaws, handle members extending outwardly of said gripping jaws at an oblique angle to the pivot axis of said jaws and adapted to be disposed in closely spaced parallel relationship when said gripping jaws are closed about said armored cable, a cutting blade pivoted to one of said handles on an axis perpendicular to the pivot axis of said gripping jaws, and a handle lever on 15 said cutting blade, said handle lever extending radially outwardly of the pivot axis of the said blade, said cutting blade having an arcuate cutting edge adapted to move into and out of cutting engagement with said armored cable upon pivotal movements of said handle lever and blade in opposite directions.

20 4. A tool for cutting armored cable comprising a pair of pivotally-connected armored cable-gripping jaws, said jaws having complementary 30 channels parallel to the axis of said pivotal connection and adapted to embrace diametrically opposite sides of said cable when said gripping jaws are closed, handle portions extending outwardly of said gripping jaws at an oblique angle 35 to the pivot axis of said jaws and adapted to be disposed in closely spaced parallel relationship when said gripping jaws are closed about said armored cable, a cutting blade pivoted to one of said handles on an axis perpendicular to the pivot 40 axis of said gripping jaws, a handle lever on said cutting blade, said handle lever extending radially outwardly of the pivot axis of said blade, said cutting blade having an arcuate cutting edge adapted to move into and out of cutting 45 engagement with said armored cable upon pivotal movements of said handle lever and blade in opposite directions, and stop means limiting pivotal movements of said handle lever and blade in one direction.

50 5. The structure defined in claim 4 in which said stop means comprises a boss on one of said handles, said boss extending in the direction of the other of said handles and said cutting blade when said gripping jaws are closed about said armored cable, and in which said handle lever is provided with an aperture adapted to receive said boss when said handle lever is aligned with its cooperating handle member.

60 6. A tool for cutting armored cable comprising a pair of pivotally-connected gripping jaws having recesses therein, armored cable-gripping jaw inserts seated in said recesses and removable therefrom, handle portions extending outwardly of said gripping members and adapted to lie in 65 closely spaced parallel relationship when said gripping jaws are closed about said armored cable, a cutting blade pivoted to one of said handles on an axis perpendicular to the pivot axis of said gripping jaws, and a handle lever on said 70 cutting blade, said handle lever extending radially outwardly of the pivot axis of said blade, the cutting edge of said blade being adapted to move into and out of cutting engagement with said armored cable upon pivotal movements of said handle lever and blade in opposite directions.

7. The structure defined in claim 6 in further combination with stop means limiting pivotal movements of said cutting blade in one direction.

8. A tool for cutting armored cable comprising a pair of pivotally-connected gripping jaws having recesses therein, armored cable-gripping jaw inserts seated in said recesses and removable therefrom, handle portions extending outwardly of said gripping jaws at an oblique angle to the pivot axis of said jaws and adapted to be disposed in closely spaced parallel relationship when said gripping jaws are closed about said armored cable, a cutting blade pivoted to one of said handles on an axis perpendicular to the pivot axis of said gripping jaws, and a handle lever on said cutting blade, said handle lever extending radially outwardly of said blade, said blade having an arcuate cutting edge adapted to move into and out of cutting engagement with said armored cable upon pivotal movements of said handle lever and blade in opposite directions.

9. A tool for cutting armored cable comprising a pair of pivotally-connected gripping jaws having recesses therein, armored cable-gripping jaw inserts seated in said recesses and removable therefrom, said gripping jaws having complementary channels parallel to the axis of said pivotal connection and adapted to embrace diametrically opposite sides of said cable when said gripping jaws are closed, handle portions extending outwardly of said gripping jaws at an oblique angle to the pivot axis of said jaws and adapted to be disposed in closely spaced parallel relationship when said gripping jaw inserts are closed about said armored cable, a cutting blade pivoted to one of said handles on an axis perpendicular to the pivot axis of said gripping jaws, a handle lever on said cutting blade, said handle lever extending radially outwardly of the pivot axis of said blade, said blade having an arcuate cutting edge adapted to move into and out of cutting engagement with said armored cable upon pivotal

movements of said handle lever and blade in opposite directions, and stop means limiting pivotal movements of said handle lever and blade in one direction.

5 10. The structure defined in claim 9 in which said stop means comprises a boss on the other of said handles, said boss extending in the direction of the other of said handles and said cutting blade when said gripping jaws are closed about said armored cable and in which said handle lever is provided with an aperture adapted to receive said boss when said handle lever is aligned with its cooperating handle member.

15 11. A tool for cutting armored cable comprising a pair of pivotally-connected gripping jaws having recesses therein, armored cable-gripping jaw inserts seated in said recesses and removable therefrom, said gripping jaw inserts having complementary channels parallel to the axis of said pivotal connection and adapted to embrace diametrically opposite sides of said cable when said gripping jaws are closed, means for preventing movements of said jaw inserts with respect to said gripping jaws axially of said pivot, detent 20 means associated with said jaw inserts and said gripping jaws for preventing accidental removal of said jaw inserts, handle portions extending outwardly of said gripping jaws and adapted to lie in closely spaced parallel relationship when 25 said jaw inserts are closed about said armored cable, a cutting blade pivoted to one of said handles on an axis perpendicular to the pivot axis of said gripping jaws, and a handle lever on said cutting blade, said handle lever extending 30 radially outwardly of the pivot axis of said blade, the cutting edge of said blade being adapted to move into and out of cutting engagement with said armored cable upon pivotal movements of said handle lever and blade in opposite directions.
